TO ENSIGN-REYNOLDS, INC., OF NEW YORK, N. Y., A CORPORATION OF NEW YORK

BLAST BURNER

Application filed September 22, 1928. Serial No. 307,636.

This invention relates to blast burners wherein gas is used as a fuel, the object being to provide an improved construction wherein the flame is maintained lighted without burning out any part of the burner.

Another object of the invention is to provide a burner of the blast type, wherein the flame may be operating under high or low pressure and be constantly maintained lighted without injuring any part of the burner.

10 In the accompanying drawings—

Figure 1 is a longitudinal vertical sectional view of a burner disclosing an embodiment of the invention, part of a supply pipe being shown in connection therewith;

15 Figure 2 is a sectional view through Figure 1 on line 2—2.

Heretofore in the use of blast burners means have been provided for keeping the flame ignited, but these means produced or caused to be produced tremendous heat near the outlet of the burner, and consequently in the course of time the burner became more or less useless.

20 In the present invention a blast burner operating in the usual manner of burners of this type is presented, but provided with special means for maintaining the gas ignited without injury to the burner.

25 In providing a structure of this kind there is supplied a burner body of tubular form having an internally-threaded section 2, into which a supply pipe 3 is screwed, as shown in

30 Figure 1. The gas from supply pipe 3 is discharged into the open space of a chamber 4 and thence it passes to the burner nozzle 5 and out through the opening 6. As the gas is moving at a comparatively high rate of speed quite often it is not ignited until

35 it is beyond the outer end 7 of the burner. By reason of this very fact the flame sometimes goes out, and in order to maintain the same lighted, a plurality of small passageways 8 are supplied in the annular flange 9

40 forming the burner opening 5. These passageways discharge into an annular chamber 10 and strike against the shoulder 11.

45 These small jets of gas lose their pressure as they pass through the chamber 10, so that 50 they are easily maintained lighted and the

flame will strike the shoulder 11 and be deflected substantially at right angles into the opening 6 whereby the various small flames from the gas passing through the passageways 8 will continually ignite the gas passing through the opening 6. Yet it will, of course, be understood that these small flames will function, or rather, will burn, even though the main flame is burning in the proper manner, that is, these small flames produce very little heat and the annular flange 12 will not become heated to any appreciable extent as it is spaced a short distance from the main flame and as the heat from the flames produced by the gas passing through the passageways 8 is negligible.

Also, the flange 9 forming the discharge opening 5 will not become heated as the gas is not ignited at this point. In this way the entire burner structure is comparatively cool at all times and will therefore function for a long time.

What is claimed is:—

1. A blast burner, comprising a body substantially tubular in formation and at one end provided with a pair of inwardly-extending flanges presenting an opening centrally of each flange, the inner flange having an opening smaller than the opening in the outer flange, said inner flange having also a plurality of small gas passageways positioned to direct gas against the inner surface of the outer flange.

2. A blast burner forming a hollow body having at one end two flanges spaced apart with a chamber therebetween, the inner flange having an opening smaller than the outer flange, the inner flange being also formed with a plurality of gas passageways surrounding said inner passageway and positioned to direct gas through said chamber and against said outer flange, said gas being adapted to be deflected laterally through the opening formed centrally of the outer flange, whereby when the gas from said passageways is ignited a plurality of lighting flames will be provided for gas passing directly through the central opening of said inner flange.

3. A blast burner, comprising a tubular

structure having a burner opening, a chamber arranged on the discharge side of the burner opening, said chamber being larger in diameter than the burner opening, and a plurality of passageways surrounding said burner opening and discharging into said chamber, the gas discharged through said passageways when ignited acting as lighting flames for the gas passing through said burner opening.

4. A blast burner, comprising a hollow body having a pair of burner openings, the inner opening being appreciably smaller than the outer opening, whereby gas passing through the inner opening will not contact with the walls of the outer opening, said burner being formed with passageways presenting a by-pass around said inner opening so as to discharge small jets of gas adjacent the walls forming the outer burner opening, said small jets of gas acting as lighting flames for the gas passing through the inner burner opening.
